(57) **CLAIM**

The ornamental design for a supporter for holding cup-like objects, as shown and described.

DESCRIPTION

FIG. 1 is a perspective view of a supporter for holding cup-like objects showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof; and
FIG. 7 is a bottom plan view thereof; and,
FIG. 8 shows the use of the invention, where those indicated by dashed lines are not claimed in the present invention.
